(57) **CLAIM**

The ornamental design for the side portion of a stirrup of a pivoting ankle brace, as shown and described.

DESCRIPTION

FIG. 1 is an outer side view of the side portion of a stirrup of a pivoting ankle brace showing our design; the inner side thereof forms no part of the claimed design;

FIG. 2 is a rear view thereof;

FIG. 3 is a front view thereof;

FIG. 4 is a top view thereof; and,

FIG. 5 is a bottom view thereof.

The broken lines show portions of the ankle brace that form no part of the claimed design.
